US0D1014759S

(12) **United States Design Patent** (10) Patent No.: **US D1,014,759 S**
(45) Date of Patent: ** Feb. 13, 2024

(54) **X-RAY IMAGING DEVICE**

(71) Applicant: **SHIMADZU CORPORATION**, Kyoto (JP)

(72) Inventor: **Ryo Takegawa**, Kyoto (JP)

(73) Assignee: **SHIMADZU CORPORATION**, Kyoto (JP)

(**) Term: **15 Years**

(21) Appl. No.: **29/843,672**

(22) Filed: **Jun. 23, 2022**

(30) **Foreign Application Priority Data**

Feb. 24, 2022 (JP) ..... 2022-003583 D

(51) LOC (14) Cl. **24-01**

(52) U.S. Cl.

USPC **D24/158**

(58) **Field of Classification Search**

(57) **CLAIM**

The ornamental design for an X-ray imaging device, as shown and described.

DESCRIPTION

FIG. 1 is a perspective view of an X-ray imaging device showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a cross-sectional elevation view of the X-ray imaging device, taken in the direction of line 8-8, of FIG. 2. Broken lines in the drawings represent portions of the X-ray imaging device that form no part of the claimed design.

1 Claim, 5 Drawing Sheets
